LIQUID DISPENSING APPARATUS

Ronald M. Wilson, Ambler, Pa., assignor, by
mesne assignments, to William M. Wilson's
Sons, Inc., Lansdale, Pa., a corporation of
Pennsylvania

Application May 28, 1946, Serial No. 672,797

7 Claims. (Cl. 222—173)

1

This invention has general reference to liquid dispensing apparatus and, more particularly, relates to the so-called metering-type of such apparatus which includes a power operated pump, as well as strainer and by-pass devices.

Dispensing apparatus of the above indicated type as heretofore constructed, while generally satisfactory for the intended purpose, are cumbersome to install, and difficult of access when repairs must be made. These disadvantages become very pronounced when such dispensing apparatus is installed for use on farms and in rural territory where experienced labor very frequently is unavailable.

Accordingly it is a particular object of this invention to overcome the noted disadvantages by dividing the apparatus or unit into two readily connectable relatively light parts of approximately equal weight and to simplify the assembly set-up thereof, whereby the unit as a whole can be readily installed, or repair thereto easily made by one man without undue physical exertion and with appreciable reduction in the initial and subsequent maintenance costs.

Another object of this invention is to provide a liquid dispensing apparatus of the metering-type which comprises an easily assembled or readily disconnected base-structure for a pump and meter unit, in association with means for the relatively independent stationary support of a driving motor.

A further object of this invention is to provide a novel form of base for the metering-pump unit of liquid dispensing apparatus of the species above referred to, which by the simple expedient of releasing two hold-fast devices can be quickly removed for servicing or repair, and just as expeditiously replaced.

While the foregoing definitions are indicative in a general way of the aims of this invention, others with ancillary advantages will be evident to those skilled in the art upon a full understanding of the construction, arrangement and assembly of the means hereinafter fully disclosed.

In the drawings:

Fig. 1 is a vertical section through the upper portion of a gasoline-service installation, embodying the improvements of this invention.

Fig. 2 is a vertical section taken approximately on the staggered plane II—II in Fig. 1 and at a right-angle thereto.

Fig. 3 is a horizontal section on the plane III—III in Fig. 1 as viewed in the direction of the angled arrows.

Fig. 4 is a fragmentary cross-section on the plane IV—IV in Fig. 1; and

2

Fig. 5 is an elevation of the complete underground installation, on a reduced scale, and illustrating how the bi-partite set-up is easily separable for the purpose of servicing or repair of the, hereinafter termed, pump-and-meter unit.

In describing the illustrated form of this invention, specific terms will be employed for the sake of clarity, but it is to be understood the scope of the invention is not to be considered as being thereby limited, each such term being intended to embrace all reasonable equivalents capable of performing the same functions for analogous purposes.

Referring first more particularly to Fig. 5, the reference character 6 designates a fragmentary portion of a liquid reservoir or gasoline storage-tank, for what is commonly known as an underground-installation, the same having a suitable fitting 7 into which the lower end of a tubular-standard or base support 8 is screw-threaded. Mounted on the upper end of the standard 8 is a socket-fitting 9 of special construction which is secured in place by radially-arranged set-screws 10.

Also referring now to Figs. 1 to 4, it is to be noted that the illustrated liquid dispensing apparatus comprises what I preferably term a "pump-and-meter" unit including a rotary-pump 11 and an associated meter 12; a motor unit or base 13, having a removable drive-connection 14 to the pump 11; a conduit 15 including a contact-box 16 for the electrical connections to the motor 13; and wiring or a cable 17 from said motor to a switch-box 18 provided with a starter-switch 19; all of said elements being enclosed within a protective housing 20.

The socket-fitting 9 is of elbow-formation in that the cap-section 21 thereof has an upset-bend 22, the lower end whereof is interiorly screw-threaded for attachment of the pump suction-pipe 23, while the upper and angularly-related end is provided with a laterally-projecting flange 24, including horizontal embossments 25 having bores 26 axially therethrough for a purpose later explained. It is also to be particularly noted that the bend 22 and flange 24 are tangential relative to the axis of the socket-fitting 9 so as to define a horizontal ledge 27 with a vertical flat 28.

The socket-fitting 9 also has an upper flat bracket-portion or ridge 29, and a medially-disposed downwardly-inclined web 30, said parts jointly affording attachment for right and left-hand motor-supporting brackets 31. Each bracket 31 is conveniently fabricated from suitable bar stock to provide a supporting section 32 bent

at 33, and inclinedly twisted at 34 into a plane at right angles to that of the supporting section 32, the terminal portion 35 of the twisting 34 being apertured for registration with a corresponding hole in the web 30 and through passage of a clamp-bolt 36. The bracket sections 32 are provided, proximate their respective ends, with holes 37 for passage of securing means 38 which engage in registering apertures through the base flange 39 of the motor 13, and whereby the latter is rigidly supported by the socket-fitting 9 as best shown in Figs. 1 and 5.

The means for seating the pump 11 consists of a combination hollow by-pass-and-strainer device, comprehensively designated 40, said device being of generally rectangular contour, as best shown in Figs. 3 and 4, with a curved-extension 41 at one end for connection of a flow-conduit 42 into the meter 12. The device 40 is formed with base pads 43, having screw-threaded bores 44 therein, for the purpose of securing said device on the platform member 45 of the housing 20, as by stud-bolts 46. In addition the device 40 is provided at one side with a flange portion 47 conformable with the lateral flange 24 of the upset-bend 22 on the socket-fitting 9 aforesaid, and whereto it is attached as by stud-bolts 48, with inter-position of a suitable gasket 49. It is also to be observed that the device 40 has a top flange 50 to which the conformatory base-flange 51 of the pump 11 is secured by suitable means 52. Interiorly, the device 40 is provided with an angular-partition 53, Fig. 4, having an aperture 54 above the level of the bottom thereof to define by-pass-and-strainer sections 55, 56 respectively, the strainer component not being shown, the top flange 50 having spaced orifices 57, 58 matching the intake and delivery ports of the pump 11, Fig. 3. The side wall 59, Fig. 4, spaced from its flange-connection 47 to the socket-fitting 9, is provided with a hole 60, aligned with the aperture 54, and a second hole 61 aligned with the bore 62 of the upset bend 22 and inlet orifice 63 from the suction-pipe 23, said holes 60 and 61 being closed-in by a plate component 64 and gasket 65, with the aid of securing means 66.

The housing 20 comprises a rectangular framework 67, see Figs. 3 and 5, preferably made of angle-section stock and having the angular corners rounded at 68, said framework having the platform 45 suitably mounted thereon to one side with its inner edge on a cross-bar 67', and braces 69 across the spacedly related corners. An inverted U-shaped channel-section 70 medially surmounted on the frame 67 has its terminal ends welded thereto at 71. The framework 67 affords support for the housing 20 which is preferably formed from suitable sheet material to the contour best shown in Figs. 1, 2 and 3, that is to say, with an arched crown or top 72 and rectangularly-related walls 73 each including an outset-panel portion and corner roundings 75, the latter being conformative with the corners 68 of the base framework 67. As shown, the housing 20 is securely attached by clamp bolts 76 and spacers 74 to the framework 67 and the channel-section 70.

From the foregoing the merits of my improved dispensing apparatus will be readily apparent, but it is desired to emphasize certain pronounced advantages over all hitherto known analogous structures. Assuming the reservoir or storage tank 6 to have been installed below ground, the first step is to screw the lower end of the base support 8 into the fitting 7, whereupon the

socket-fitting 9 with the attached suction-pipe 23 and motor 13, as a previously assembled unit, is lowered onto the base support 8 and rigidly secured in position by simply tightening-up the set-screws 10. The by-pass-and-strainer device 40, together with the pump 11, meter 12, switch-box 18 and cable 17, as well as the other associated parts also having been previously assembled and mounted in the housing 20 as a unit, which one man can easily pick up and carry, is then placed in position by resting the side-flange 47 thereof on the horizontal ledge 21 of the socket-fitting 9. With this preparation the latter unit is readily alignable, by lateral movement, until the holes 13 in the respective flanges 47 and 24 are in registration, when the two stud-bolts 48 are inserted and tightened-up. All that remains to be done now is to clamp the cable 17 to the motor binding-post 77, and to apply the V-belt or drive connection 14 from the motor 13 to the pump 11. In the event of trouble arising in any part of pump-and-meter unit 11, 12 due to clogging, sticking or wear; said unit together with the housing 20 can be easily removed by simply re-tracting the stud-bolts 48 from engagement in the flange 47 of the by-pass-and-strainer device 40, releasing the V-belt 14 from the pump 11 and uncoupling the cable 17 from the motor binding-post 77. These parts in assembly can be thereupon lifted-off as a unit, relaced with a corresponding unit, or carried to a repair depot for servicing where tools, work-benches and spare parts are available. This procedure is also an important advance over the prevailing practice of having to make all repairs in the field, often under unfavorable conditions. Another noteworthy advantage inherent in my invention is that when the side flange 47 of the removable unit 40 is initially rested on the edge of the horizontal-ledge 21 of the stationary motor base as shown, said unit will not slide-off or from its inclination from the vertical since the base flange 39 and bend 33 of the bracket 31 jointly and temporarily serve as an abutment guide during movement of the unit laterally and into vertical position, so that the holes in the respective flanges 24, 47 are easily brought into proper registration ready for insertion of the stud-bolts 48.

In conclusion, while I have shown and described a preferred embodiment of my invention, it is to be expressly understood, that I do not confine myself to the precise details of construction set forth by way of illustration. The bi-partite dispensing apparatus structure as a unit may be mounted on any other desirable base support than the standard 8, and that changes and variations may be made therein without departing from the spirit of the invention within the scope of the following claims.

Having thus described my invention, I claim:

1. In liquid dispensing apparatus the combination of a tubular standard for attachment at one end to an underground liquid storage-tank; a socket-fitting seatable on the other end of the standard, said socket-fitting including a hollow bend with means for attachment thereto of a suction-conduit for entry into the storage-tank, and means affording rigid bearing for a motor; a relatively removable by-pass-and-strainer device embodying bearing for the pump and meter assembly of the apparatus; and means for securing the by-pass-and-strainer device to the socket-fitting bearing portion with capacity for quick release of said device for replacement by another, or for repair.

5

2. In liquid dispensing apparatus, the combination of a tubular-support for attachment at its lower end to an underground liquid storage tank with projection above ground level; a socket-fitting seatable on the upper end of said tubular support, said fitting including an elbow-bend with means for attachment thereto of a suction pipe for passage through said support into the tank aforesaid, and means affording rigid bearing for a motor; a relatively removable by-pass-and-strainer device embodying a bearing for the pump and meter assembly of the apparatus; means for attaching the socket-fitting to the hollow tubular-support with capacity for quick release; and means for rigidly connecting the by-pass-and-strainer device to the socket-fitting with provision for easy detachment therefrom wherever desirable or expedient.

3. A bi-partite liquid dispensing apparatus comprising a base including a seating-portion; means defining a bore through the base, an attachment flange with an angularly-related ledge projecting outwardly beyond the plane of said flange, and means affording rigid bearing for a motor; a by-pass-and-strainer device having a portion engageable on the base ledge, and said device affording support for a pump and meter assembly; and means for attaching the base to the by-pass-and-strainer device with capacity for release whenever desirable or expedient.

4. A bi-partite liquid dispensing apparatus, comprising a base including a seating-portion; means defining a bore through the base, an attachment flange with an angularly-related ledge projecting outwardly beyond the plane of said flange, and means affording rigid bearing for a motor; a by-pass-and-strainer device having a portion engageable on the base ledge, and said device affording support for a pump and meter assembly; means for attaching the base to the by-pass-and-strainer device with capacity for release therefrom whenever desirable; and a closure housing secured to the by-pass-and-strainer device with capacity to include therein the motor base when said device is attached thereto.

5. A bi-partite liquid dispensing apparatus in accordance with claim 4, wherein the base is in the form of a socket-fitting including a cap-section and associated up-set elbow having a bore therethrough with the lower end adapted for connection of a suction conduit; an inset vertical flange at the upper end of said elbow with a subjacent ledge; spaced embossments to the rear of said flange with through bores; a transverse ridge across the socket-fitting with

6

5 a medially-located downwardly-inclined web to the cap-section; and wherein the bearing means for the motor comprises spaced brackets, each such bracket being bent intermediate the ends to define a horizontal supporting section and a relatively inclined section, with the latter section turned into a plane at right angles to that of the former section; and means whereby the terminal ends of the spaced brackets are securable to the elbow transverse ridge and inclined web respectively.

10 15 20 25 6. A bi-partite liquid dispensing apparatus in accordance with claim 4, wherein the by-pass-and-strainer device consists of a hollow generally rectangular unit with a curved extension at one end adapted for connection thereto of a flow-conduit; a flange portion at one side of said device for mating connection to the base attachment flange with seating on the angularly-related ledge thereof; a flange on top of the device, conformatory with the base of the sustained pump, and having flow and return orifices therethrough; an angular-partition in the device to define by-pass-and-strainer sections therein; and the opposed side wall of the device having spaced holes therein with an associated removable closure component, for the purposes specified.

7. A bi-partite liquid dispensing apparatus in accordance with claim 4, wherein the closure housing comprises a rectangular framework of suitable section stock with the angular corners rounded; a platform to one side of the framework for seating reception and attachment of the apparatus pump and meter, with braces across the spacedly related corners of said framework; an inverted U-shaped section medially surmounting the framework and having its ends integrated thereto; a suitable sheet material covering having an arched crown and rectangular related walls supported over the framework by the U-shaped section and means whereby the covering is secured to the framework at its lower end and also to said U-shaped section.
